METHOD FOR GASIFYING FINELY DIVIDED
FUEL WITH CIRCULATING GAS

Hans Schmalfeldt, Kassel, Germany

Application November 7, 1935, Serial No. 48,729
In Germany November 26, 1934

3 Claims. (Cl. 48—202)

This invention relates to the process of producing gas from finely divided fuel and has reference particularly to the application of this process to fine or dust coal.

5 My invention has for its object to introduce into the process of producing gas the step of providing a superpressure at any point in the path of travel of the fuel between the gasifier and each regenerator.

10 In the accompanying drawing, one form of apparatus, adapted to carry out the steps of the process is illustratively exemplified.

Referring to the drawing, *a* denotes a gasifier, and *b* the nozzles by means of which the finely divided fuel is introduced into the gasifier. The 15 circulating gas heated to a high temperature by the regenerators *d*₁ and *d*₂ enters the gasifier alternately at *c*₁ and *c*₂, gasifies the coal dust in giving up heat, and escapes together with the 20 freshly formed combustible gas at *e*. The regenerators *d*₁ and *d*₂ are alternately heated by the furnaces *f*₁ and *f*₂, the gas- and air conduits *g*₁, *h*₁ or *g*₂ and *h*₂ respectively of the corresponding furnaces to be opened each time during the heating and closed each time during the cooling of the regenerators. The waste gas slide valves *m*₁ 25 and *m*₂ are likewise alternately open and closed during the heating and gasifying. The circulating gas to be pre-heated, consisting of water vapour or of water vapour mixed with water gas, or of a mixture of water vapour and the gas produced, alternately enters the regenerators 30 through the slide valves *p*₁ and *p*₂ and comes into the gasifier through the connections *c*₁ and *c*₂.

The inlet passages for the hot circulating gases 700°—1600° C. into the gasifiers or the connecting pipe conduits between regenerator and gasifier have either at the entrance into the gasifier 40 or at some other point a kind of nozzle or a narrowing so that a certain high pressure (superpressure of about 200 to 5,000 mms. water column) is necessary to force the hot circulating gas out of the corresponding regenerator into the gasifier. (The circulating gas always contains steam, e. g. together with water gas of different composition or hydrogen and carbon dioxide or producer gas.) The narrowing is proportioned 45 preferably in such a way that the cross section at this point is reduced for 5—80%. The nozzle-shaped narrowing of the connecting conduits need not be arranged at the entrance into the gasifier, but may be provided at any other point of the connecting conduit. However, the narrowing of the conduit at the entrance into the gasi-

fier presents the advantage that the high admission speed of the hot circulating gases flowing into the gasifier causes a good circulation or a continuous interwhirling of the gas masses in the gasifier. Consequently the fine coal particles to be gasified are permanently maintained in suspension so that the gasification is accelerated.

If the nozzle, for example, is so dimensioned that the pressure in front of the nozzle during the flow of the circulating gas is about 2000 10 mms. water column and if the pressure difference is maintained at 2 mms. water column between the gasifier and the regenerator on heat, the value of the gas flowing in an undesired direction on the heating side is only 15

$$\frac{\sqrt{2}}{\sqrt{2000}} = \frac{31}{1000} \text{ th}$$

part of the circulating current, i. e. therefore only about a 30th part of the quantity of circulating gas flows either as flue gas into the circulating gas or as circulating gas out of the gasifier into the flue gas of the generator on heat. The quantity of gas flowing in an undesired direction has thus been reduced to an allowable 20 minimum. 25

However, even when the pressure difference between gasifier and the regenerator on heat is considerably greater, for example amounts to 20 mms. water column, the value of the gas flowing 30 in an undesired direction is always only a tenth part of the circulating gas.

The superpressure produced in the connecting path between the regenerating zone and the gasifying zone for sealing may be used advantageously to circulate or to maintain in movement the gas masses in the gasifying zone by means of the speed increase of the flowing gases resulting from said superpressure during the passage of the gas stream from the gasifying regenerator; thereby the carbonaceous particles are kept in suspension. 35 40

Consequently the construction of the gas inlet according to the invention, e. g. the nozzle-shaped construction of the circulating gas inlet, 45 results in such a reduction of the quantity of unaccounted for gas, that hot valves can be readily omitted, so that a regulated, economical working is possible. A slight dilution of the circulating gas can also be put up with, same as a 50 slight loss of circulating gas.

It is, however, possible, according to the invention, to obtain an absolutely tight closure if care is taken that the pressure in the regenerator on heat is always higher (0.1—100 mms. water 55

column) than the pressure in the gasifier, which can always be attained by corresponding adjustment of the waste gas slide valves m . The measure necessary for this consists in introducing sealing steam into the connecting conduits between the generator on heat and the gasifier prior to the outlet from the nozzle or prior to the point where the superpressure must be overcome viz. the constriction. According to the drawing o_1 and o_2 with valves s_1 and s_2 serve this purpose, and are correspondingly controlled and always maintained open on the heating side and closed on the gasifying side. The pressure difference prevailing between the gasifier and the heating regenerator can fluctuate within certain limits. The quantity of sealing steam is so adjusted, that during the greatest permissible pressure difference this is just sufficient to force the whole quantity of sealing steam into the gasifier. In the case of a small pressure difference only a portion of the sealing steam flows into the gasifier, whereas the remainder passes off into the regenerator on heat. The steam, introduced into the gasifier, evidently does not cause a dilution of the circulating gas, but rather has a useful effect, as this steam is utilized to assist the gasification. The quantity of steam passing into the heating regenerator likewise does not have a prejudicial effect as it is relatively small. In any case gas losses and dilution of the generated gas and also afterburning at any point not desired are avoided.

The difference in pressure between the regenerator on heat and the gasifier may be of the range of 0.3-4 mms. water column pressure but it may be also 80-100 mms. or, if necessary, slightly more. The pressure in the gasifier itself may vary between any limits; e. g. it may be regulated to 20-350 mms. water column.

The carbonaceous fuel, finely divided, may be e. g.: mineral coal, charcoal, lignite, peat or the like.

Naturally the pressure in the gasifying regenerator must be higher than in the gasifier.

Having thus described the invention, I claim:

1. In the herein described process for gasifying finely divided carbonaceous fuel by periodically circulating gases in series through a regenerating zone and a gasifying zone and in the alternate

periods reheating the gases in the regenerating zone to 700°-1600° C., the steps which comprise permanently choking the flow of the gas at a predetermined point of the path from the regenerating zone to the gasifying zone, producing a substantial pressure difference between said two zones during the circulation period, and introducing sealing steam into said path during the heating period.

2. In the herein described process for gasifying finely divided carbonaceous fuel by periodically circulating gases in series through a regenerating zone and a gasifying zone and in the alternate periods reheating the gases in said regenerating zone to 700°-1600° C., the steps which comprise permanently choking the gas flow of the gas at a predetermined point of the path from the regenerating zone to the gasifying zone, producing a pressure difference of about 200-5000 mms. water column between said two zones during the circulation period, and introducing sealing steam into said path during the heating period, the pressure in the regenerating zone being kept during the latter period from 0.1 to 100 mms. water column higher than in the gasifying zone by regulating the amount of waste gas discharged from the regenerating zone during the heating period.

3. In the herein described process for gasifying finely divided carbonaceous fuel in two alternating periods, in which gases are circulated in series through a regenerating zone and a gasifying zone and heated to 700°-1600° C. in a second regenerating zone during one of said periods, while the gases are heated to 700°-1600° C. in said first-mentioned regenerating zone and circulated in series through said second regenerating zone and the gasifying zone during the alternate period, the steps which comprise permanently choking the flow of gas at two predetermined points in the paths from said regenerating zones, respectively, to said gasifying zone, producing a substantial pressure difference between the regenerating zone on circulation and the gasifying zone, and introducing sealing steam into the path between said regenerating zone on heat and the gasifying zone.

HANS SCHMALFELDT.
